G. Smith and H. Brown, of Philadelphia, Penn.

Assign to

Abbott and Noble, of same place.

Letters Patent No 1829-Dated Oct. 6th 1868.

Design for a Cooking Stove.

The schedule referred to in these Letters Patent and making part of the same.

To all whom it may concern:

Be it known that we, G. Smith, and H. Brown, of Philadelphia, County of Philadelphia, State of Pennsylvania, have invented or produced a new and original design for a Cook Stove; and we do hereby declare the accompanying drawing, with the following explanation of the same, to form a full, clear, and exact description of the said design.

Fig. 1, of the drawing represents the side plate of the stove.

Fig. 2, the lower front plate;

Fig. 3, the upper front plate;

Fig. 4, the lower top plate;

Fig. 5, the upper top plate;

Fig. 6, the bottom plate.

Des. 1829

Fig. 7. the back plate, and
Fig. 8. one of the legs.

On the side plate (fig. 1) are two doors A, and B, the edges of which are bordered by plain mouldings, the surfaces being ornamented with the raised ornaments clearly shown in the drawing. The edge x, of the side plate has an ornamental beading; the other edges of the plates having a plain moulding.

The lower front plate, fig. 2, has an ornamental beading on each of the side edges similar to the moulding on the edge x, of the side plate; the door C, having ornaments similar to those on the door B.

The ornamental design on the upper front plate (fig. 3) is similar to that on the door A, and is enclosed in a panel surrounded by a plain beading y; that portion of each end of the plate outside of the panels, having an ornamental figure surrounded by the scroll work shown in the drawing.

The lower top plate Fig. 4, is surrounded by a plain moulding, there being a similar plain moulding on three of the edges of the upper top plate, Fig. 5, the front edge, however, of this plate has an ornamental beading y.

Round the front and side edges of the base plate, Fig. 6, is an ornamental beading x.

The back plate (Fig. 7) is edged with a plain moulding and has a central panel ornamented with a design similar to that on the door A.

The ornamentation on the leg (Fig. 8) is clearly shown in the drawing.

We claim the ornamental figures and forms represented in and by the accompanying drawing, the whole forming an ornamental design for the plates of a

Dec. 1829

cook stove.

In testimony whereof, we have signed our names
to this specification in the presence of two subscribing
witnesses.
